US0D1107743S

(12) United States Design Patent (10) Patent No.: US D1,107,743 S
 (45) Date of Patent:  Dec. 30, 2025

(54) DISPLAY SCREEN WITH GRAPHICAL USER INTERFACE

(71) Applicant: Rohm and Haas Company, Collegeville, PA (US)

(72) Inventors: James Nicolas Pagaduan, Phoenixville, PA (US); Sun Hye Kim, Houston, TX (US)

(73) Assignee: Rohm and Haas Company, Collegeville, PA (US)

() Term: 15 Years

(21) Appl. No.: 29/952,932

(22) Filed: Jul. 18, 2024

(51) LOC (15) Cl. 14-04

(52) U.S. Cl.

USPC D14/486

(58) Field of Classification Search

USPC D14/485-495
 CPC .. G06F 3/0481; G06F 3/0482; G06F 3/0483;
 G06F 3/04815; G06F 3/04847; G06F
 3/0485; G06F 3/048; G06F 3/0488; G06F
 3/04886; Y10T 428/2436

See application file for complete search history.

(56) References Cited

U.S. PATENT DOCUMENTS

D946,020 S * 3/2022 Nuttbrown D14/491
 D1,012,961 S * 1/2024 Modi D14/486

D1,015,352 S * 2/2024 Bieter D14/485
 D1,015,354 S * 2/2024 Bieter D14/485
 D1,030,781 S * 6/2024 Khan D14/485
 D1,033,458 S * 7/2024 Khan D14/485
 D1,037,274 S * 7/2024 Narsipur D14/485
 D1,051,927 S * 11/2024 Maheshwari D14/486
 D1,061,585 S * 2/2025 Indorf D14/490
 D1,071,951 S * 4/2025 Modi D14/486
 D1,074,691 S * 5/2025 Berkowitz D14/485
 D1,076,956 S * 5/2025 Narsipur D14/485
 2019/0113345 A1 * 4/2019 Stewart G06F 3/0483

* cited by examiner

Primary Examiner — Katherine A Holbrow

(74) Attorney, Agent, or Firm — Arthur R. Rogers

(57) CLAIM

The ornamental design for a display screen with graphical user interface, as shown and described.

DESCRIPTION

FIG. 1 is a front view of a display screen with graphical user interface, showing a first embodiment of the new design; FIG. 2 is a second embodiment thereof; FIG. 3 is a third embodiment thereof; FIG. 4 is a fourth embodiment thereof; FIG. 5 is a fifth embodiment thereof; FIG. 6 is a sixth embodiment thereof; and, FIG. 7 is a seventh embodiment thereof.

The broken lines in the drawings illustrate portions of the graphical user interface that form no part of the claimed design.

1 Claim, 7 Drawing Sheets

Compare Performance Specifications

Enter Target Specifications
Step 1: Select paint type
Standard
Step 2: Select paint specifications
Category
Binder Identity
Specification
PASURANK 3427
Data Type
Category
Target Value
Yes
Add specification

Selected Targets
Paint Type: Standard
Requirement	Specification	Data Type	Target Value
☒ Binder Identity	PASURANK 3427	Category	Yes

View Result

= Pass Spec
 0
 1

Pass Fail

State	Pass Spec	# of pass (excluding not specified)
Federated	specification not stated	0
Alaska	specification not stated	0
Alabama	specification not stated	0
Arkansas	specification not stated	0

Compare Performance Specifications⑦
Enter Target Specifications
Step 1: Select paint type
Category	Select
Specification	Select
Data Type	Select
Target Value ⑦	Add specification
View Result
Selected Targets Paint Type: ☐ Requirement ☐ Specification ☐ Data Type ☐ Target Value
☐ Pass ☐ Fail

FIG. 1

Compare Performance Specifications
Enter Target Specifications		Selected Targets
Step 1: Select paint type		Paint Type: Standard
Standard		Requirement	Specification	Data Type	Target Value	Yes
		X	Standard	FASTRACK	3427	Category
Step 2: Select paint specifications
Category	Standard	Requirement	Specification	Data Type	Target Value	Yes
Specification	FASTRACK	X	Standard	FASTRACK	3427	Category
Data Type	Category	X	Standard	FASTRACK	3427	Category
Target Value	Yes	X	Standard	FASTRACK	3427	Category
Add specification View Result
☐ Pass Spec ☐ Fail
☐ Pass ☐ Fail = Pass Spec 0 Fail Spec 1
<table border="1"> <thead> <tr> <th>State</th> <th>Filter</th> <th>Actions</th> <th>FASTRACK</th> <th>3427</th> <th>Category</th> <th>Pass Spec</th> </tr> </thead> <tbody> <tr> <td>Florida</td> <td>Filter</td> <td>Actions</td> <td>Specification not stated</td> <td>3427</td> <td>Category</td> <td>Pass Spec</td> </tr> <tr> <td>Penns</td> <td>Filter</td> <td>Actions</td> <td>Specification not stated</td> <td>3427</td> <td>Category</td> <td>Pass Spec</td> </tr> <tr> <td>Alaska</td> <td>Filter</td> <td>Actions</td> <td>Specification not stated</td> <td>3427</td> <td>Category</td> <td>Pass Spec</td> </tr> <tr> <td>Alabama</td> <td>Filter</td> <td>Actions</td> <td>Specification not stated</td> <td>3427</td> <td>Category</td> <td>Pass Spec</td> </tr> <tr> <td>Akansas</td> <td>Filter</td> <td>Actions</td> <td>Specification not stated</td> <td>3427</td> <td>Category</td> <td>Pass Spec</td> </tr> <tr> <td>Arizona</td> <td>Filter</td> <td>Actions</td> <td>Specification not stated</td> <td>3427</td> <td>Category</td> <td>Pass Spec</td> </tr> <tr> <td>Arkansas</td> <td>Filter</td> <td>Actions</td> <td>Specification not stated</td> <td>3427</td> <td>Category</td> <td>Pass Spec</td> </tr> <tr> <td>California</td> <td>Filter</td> <td>Actions</td> <td>Specification not stated</td> <td>3427</td> <td>Category</td> <td>Pass Spec</td> </tr> <tr> <td>Colorado</td> <td>Filter</td> <td>Actions</td> <td>Specification not stated</td> <td>3427</td> <td>Category</td> <td>Pass Spec</td> </tr> <tr> <td>Connecticut</td> <td>Filter</td> <td>Actions</td> <td>Specification not stated</td> <td>3427</td> <td>Category</td> <td>Pass Spec</td> </tr> <tr> <td>Delaware</td> <td>Filter</td> <td>Actions</td> <td>Specification not stated</td> <td>3427</td> <td>Category</td> <td>Pass Spec</td> </tr> <tr> <td>Florida</td> <td>Filter</td> <td>Actions</td> <td>Specification not stated</td> <td>3427</td> <td>Category</td> <td>Pass Spec</td> </tr> <tr> <td>Georgia</td> <td>Filter</td> <td>Actions</td> <td>Specification not stated</td> <td>3427</td> <td>Category</td> <td>Pass Spec</td> </tr> <tr> <td>Hawaii</td> <td>Filter</td> <td>Actions</td> <td>Specification not stated</td> <td>3427</td> <td>Category</td> <td>Pass Spec</td> </tr> <tr> <td>Idaho</td> <td>Filter</td> <td>Actions</td> <td>Specification not stated</td> <td>3427</td> <td>Category</td> <td>Pass Spec</td> </tr> <tr> <td>Illinois</td> <td>Filter</td> <td>Actions</td> <td>Specification not stated</td> <td>3427</td> <td>Category</td> <td>Pass Spec</td> </tr> <tr> <td>Indiana</td> <td>Filter</td> <td>Actions</td> <td>Specification not stated</td> <td>3427</td> <td>Category</td> <td>Pass Spec</td> </tr> <tr> <td>Iowa</td> <td>Filter</td> <td>Actions</td> <td>Specification not stated</td> <td>3427</td> <td>Category</td> <td>Pass Spec</td> </tr> <tr> <td>Kansas</td> <td>Filter</td> <td>Actions</td> <td>Specification not stated</td> <td>3427</td> <td>Category</td> <td>Pass Spec</td> </tr> <tr> <td>Louisiana</td> <td>Filter</td> <td>Actions</td> <td>Specification not stated</td> <td>3427</td> <td>Category</td> <td>Pass Spec</td> </tr> <tr> <td>Maine</td> <td>Filter</td> <td>Actions</td> <td>Specification not stated</td> <td>3427</td> <td>Category</td> <td>Pass Spec</td> </tr> <tr> <td>Massachusetts</td> <td>Filter</td> <td>Actions</td> <td>Specification not stated</td> <td>3427</td> <td>Category</td> <td>Pass Spec</td> </tr> <tr> <td>Michigan</td> <td>Filter</td> <td>Actions</td> <td>Specification not stated</td> <td>3427</td> <td>Category</td> <td>Pass Spec</td> </tr> <tr> <td>Minnesota</td> <td>Filter</td> <td>Actions</td> <td>Specification not stated</td> <td>3427</td> <td>Category</td> <td>Pass Spec</td> </tr> <tr> <td>Mississippi</td> <td>Filter</td> <td>Actions</td> <td>Specification not stated</td> <td>3427</td> <td>Category</td> <td>Pass Spec</td> </tr> <tr> <td>Missouri</td> <td>Filter</td> <td>Actions</td> <td>Specification not stated</td> <td>3427</td> <td>Category</td> <td>Pass Spec</td> </tr> <tr> <td>Montana</td> <td>Filter</td> <td>Actions</td> <td>Specification not stated</td> <td>3427</td> <td>Category</td> <td>Pass Spec</td> </tr> <tr> <td>Nebraska</td> <td>Filter</td> <td>Actions</td> <td>Specification not stated</td> <td>3427</td> <td>Category</td> <td>Pass Spec</td> </tr> <tr> <td>Nevada</td> <td>Filter</td> <td>Actions</td> <td>Specification not stated</td> <td>3427</td> <td>Category</td> <td>Pass Spec</td> </tr> <tr> <td>New Hampshire</td> <td>Filter</td> <td>Actions</td> <td>Specification not stated</td> <td>3427</td> <td>Category</td> <td>Pass Spec</td> </tr> <tr> <td>New Jersey</td> <td>Filter</td> <td>Actions</td> <td>Specification not stated</td> <td>3427</td> <td>Category</td> <td>Pass Spec</td> </tr> <tr> <td>New Mexico</td> <td>Filter</td> <td>Actions</td> <td>Specification not stated</td> <td>3427</td> <td>Category</td> <td>Pass Spec</td> </tr> <tr> <td>New York</td> <td>Filter</td> <td>Actions</td> <td>Specification not stated</td> <td>3427</td> <td>Category</td> <td>Pass Spec</td> </tr> <tr> <td>North Carolina</td> <td>Filter</td> <td>Actions</td> <td>Specification not stated</td> <td>3427</td> <td>Category</td> <td>Pass Spec</td> </tr> <tr> <td>North Dakota</td> <td>Filter</td> <td>Actions</td> <td>Specification not stated</td> <td>3427</td> <td>Category</td> <td>Pass Spec</td> </tr> <tr> <td>Ohio</td> <td>Filter</td> <td>Actions</td> <td>Specification not stated</td> <td>3427</td> <td>Category</td> <td>Pass Spec</td> </tr> <tr> <td>Oklahoma</td> <td>Filter</td> <td>Actions</td> <td>Specification not stated</td> <td>3427</td> <td>Category</td> <td>Pass Spec</td> </tr> <tr> <td>Oregon</td> <td>Filter</td> <td>Actions</td> <td>Specification not stated</td> <td>3427</td> <td>Category</td> <td>Pass Spec</td> </tr> <tr> <td>Penns</td> <td>Filter</td> <td>Actions</td> <td>Specification not stated</td> <td>3427</td> <td>Category</td> <td>Pass Spec</td> </tr> <tr> <td>Rhode Island</td> <td>Filter</td> <td>Actions</td> <td>Specification not stated</td> <td>3427</td> <td>Category</td> <td>Pass Spec</td> </tr> <tr> <td>South Carolina</td> <td>Filter</td> <td>Actions</td> <td>Specification not stated</td> <td>3427</td> <td>Category</td> <td>Pass Spec</td> </tr> <tr> <td>South Dakota</td> <td>Filter</td> <td>Actions</td> <td>Specification not stated</td> <td>3427</td> <td>Category</td> <td>Pass Spec</td> </tr> <tr> <td>Tennessee</td> <td>Filter</td> <td>Actions</td> <td>Specification not stated</td> <td>3427</td> <td>Category</td> <td>Pass Spec</td> </tr> <tr> <td>Texas</td> <td>Filter</td> <td>Actions</td> <td>Specification not stated</td> <td>3427</td> <td>Category</td> <td>Pass Spec</td> </tr> <tr> <td>Utah</td> <td>Filter</td> <td>Actions</td> <td>Specification not stated</td> <td>3427</td> <td>Category</td> <td>Pass Spec</td> </tr> <tr> <td>Vermont</td> <td>Filter</td> <td>Actions</td> <td>Specification not stated</td> <td>3427</td> <td>Category</td> <td>Pass Spec</td> </tr> <tr> <td>Virginia</td> <td>Filter</td> <td>Actions</td> <td>Specification not stated</td> <td>3427</td> <td>Category</td> <td>Pass Spec</td> </tr> <tr> <td>Washington</td> <td>Filter</td> <td>Actions</td> <td>Specification not stated</td> <td>3427</td> <td>Category</td> <td>Pass Spec</td> </tr> <tr> <td>West Virginia</td> <td>Filter</td> <td>Actions</td> <td>Specification not stated</td> <td>3427</td> <td>Category</td> <td>Pass Spec</td> </tr> <tr> <td>Wisconsin</td> <td>Filter</td> <td>Actions</td> <td>Specification not stated</td> <td>3427</td> <td>Category</td> <td>Pass Spec</td> </tr> <tr> <td>Wyoming</td> <td>Filter</td> <td>Actions</td> <td>Specification not stated</td> <td>3427</td> <td>Category</td> <td>Pass Spec</td> </tr> </tbody> </table>							State	Filter	Actions	FASTRACK	3427	Category	Pass Spec	Florida	Filter	Actions	Specification not stated	3427	Category	Pass Spec	Penns	Filter	Actions	Specification not stated	3427	Category	Pass Spec	Alaska	Filter	Actions	Specification not stated	3427	Category	Pass Spec	Alabama	Filter	Actions	Specification not stated	3427	Category	Pass Spec	Akansas	Filter	Actions	Specification not stated	3427	Category	Pass Spec	Arizona	Filter	Actions	Specification not stated	3427	Category	Pass Spec	Arkansas	Filter	Actions	Specification not stated	3427	Category	Pass Spec	California	Filter	Actions	Specification not stated	3427	Category	Pass Spec	Colorado	Filter	Actions	Specification not stated	3427	Category	Pass Spec	Connecticut	Filter	Actions	Specification not stated	3427	Category	Pass Spec	Delaware	Filter	Actions	Specification not stated	3427	Category	Pass Spec	Florida	Filter	Actions	Specification not stated	3427	Category	Pass Spec	Georgia	Filter	Actions	Specification not stated	3427	Category	Pass Spec	Hawaii	Filter	Actions	Specification not stated	3427	Category	Pass Spec	Idaho	Filter	Actions	Specification not stated	3427	Category	Pass Spec	Illinois	Filter	Actions	Specification not stated	3427	Category	Pass Spec	Indiana	Filter	Actions	Specification not stated	3427	Category	Pass Spec	Iowa	Filter	Actions	Specification not stated	3427	Category	Pass Spec	Kansas	Filter	Actions	Specification not stated	3427	Category	Pass Spec	Louisiana	Filter	Actions	Specification not stated	3427	Category	Pass Spec	Maine	Filter	Actions	Specification not stated	3427	Category	Pass Spec	Massachusetts	Filter	Actions	Specification not stated	3427	Category	Pass Spec	Michigan	Filter	Actions	Specification not stated	3427	Category	Pass Spec	Minnesota	Filter	Actions	Specification not stated	3427	Category	Pass Spec	Mississippi	Filter	Actions	Specification not stated	3427	Category	Pass Spec	Missouri	Filter	Actions	Specification not stated	3427	Category	Pass Spec	Montana	Filter	Actions	Specification not stated	3427	Category	Pass Spec	Nebraska	Filter	Actions	Specification not stated	3427	Category	Pass Spec	Nevada	Filter	Actions	Specification not stated	3427	Category	Pass Spec	New Hampshire	Filter	Actions	Specification not stated	3427	Category	Pass Spec	New Jersey	Filter	Actions	Specification not stated	3427	Category	Pass Spec	New Mexico	Filter	Actions	Specification not stated	3427	Category	Pass Spec	New York	Filter	Actions	Specification not stated	3427	Category	Pass Spec	North Carolina	Filter	Actions	Specification not stated	3427	Category	Pass Spec	North Dakota	Filter	Actions	Specification not stated	3427	Category	Pass Spec	Ohio	Filter	Actions	Specification not stated	3427	Category	Pass Spec	Oklahoma	Filter	Actions	Specification not stated	3427	Category	Pass Spec	Oregon	Filter	Actions	Specification not stated	3427	Category	Pass Spec	Penns	Filter	Actions	Specification not stated	3427	Category	Pass Spec	Rhode Island	Filter	Actions	Specification not stated	3427	Category	Pass Spec	South Carolina	Filter	Actions	Specification not stated	3427	Category	Pass Spec	South Dakota	Filter	Actions	Specification not stated	3427	Category	Pass Spec	Tennessee	Filter	Actions	Specification not stated	3427	Category	Pass Spec	Texas	Filter	Actions	Specification not stated	3427	Category	Pass Spec	Utah	Filter	Actions	Specification not stated	3427	Category	Pass Spec	Vermont	Filter	Actions	Specification not stated	3427	Category	Pass Spec	Virginia	Filter	Actions	Specification not stated	3427	Category	Pass Spec	Washington	Filter	Actions	Specification not stated	3427	Category	Pass Spec	West Virginia	Filter	Actions	Specification not stated	3427	Category	Pass Spec	Wisconsin	Filter	Actions	Specification not stated	3427	Category	Pass Spec	Wyoming	Filter	Actions	Specification not stated	3427	Category	Pass Spec
State	Filter	Actions	FASTRACK	3427	Category	Pass Spec
Florida	Filter	Actions	Specification not stated	3427	Category	Pass Spec
Penns	Filter	Actions	Specification not stated	3427	Category	Pass Spec
Alaska	Filter	Actions	Specification not stated	3427	Category	Pass Spec
Alabama	Filter	Actions	Specification not stated	3427	Category	Pass Spec
Akansas	Filter	Actions	Specification not stated	3427	Category	Pass Spec
Arizona	Filter	Actions	Specification not stated	3427	Category	Pass Spec
Arkansas	Filter	Actions	Specification not stated	3427	Category	Pass Spec
California	Filter	Actions	Specification not stated	3427	Category	Pass Spec
Colorado	Filter	Actions	Specification not stated	3427	Category	Pass Spec
Connecticut	Filter	Actions	Specification not stated	3427	Category	Pass Spec
Delaware	Filter	Actions	Specification not stated	3427	Category	Pass Spec
Florida	Filter	Actions	Specification not stated	3427	Category	Pass Spec
Georgia	Filter	Actions	Specification not stated	3427	Category	Pass Spec
Hawaii	Filter	Actions	Specification not stated	3427	Category	Pass Spec
Idaho	Filter	Actions	Specification not stated	3427	Category	Pass Spec
Illinois	Filter	Actions	Specification not stated	3427	Category	Pass Spec
Indiana	Filter	Actions	Specification not stated	3427	Category	Pass Spec
Iowa	Filter	Actions	Specification not stated	3427	Category	Pass Spec
Kansas	Filter	Actions	Specification not stated	3427	Category	Pass Spec
Louisiana	Filter	Actions	Specification not stated	3427	Category	Pass Spec
Maine	Filter	Actions	Specification not stated	3427	Category	Pass Spec
Massachusetts	Filter	Actions	Specification not stated	3427	Category	Pass Spec
Michigan	Filter	Actions	Specification not stated	3427	Category	Pass Spec
Minnesota	Filter	Actions	Specification not stated	3427	Category	Pass Spec
Mississippi	Filter	Actions	Specification not stated	3427	Category	Pass Spec
Missouri	Filter	Actions	Specification not stated	3427	Category	Pass Spec
Montana	Filter	Actions	Specification not stated	3427	Category	Pass Spec
Nebraska	Filter	Actions	Specification not stated	3427	Category	Pass Spec
Nevada	Filter	Actions	Specification not stated	3427	Category	Pass Spec
New Hampshire	Filter	Actions	Specification not stated	3427	Category	Pass Spec
New Jersey	Filter	Actions	Specification not stated	3427	Category	Pass Spec
New Mexico	Filter	Actions	Specification not stated	3427	Category	Pass Spec
New York	Filter	Actions	Specification not stated	3427	Category	Pass Spec
North Carolina	Filter	Actions	Specification not stated	3427	Category	Pass Spec
North Dakota	Filter	Actions	Specification not stated	3427	Category	Pass Spec
Ohio	Filter	Actions	Specification not stated	3427	Category	Pass Spec
Oklahoma	Filter	Actions	Specification not stated	3427	Category	Pass Spec
Oregon	Filter	Actions	Specification not stated	3427	Category	Pass Spec
Penns	Filter	Actions	Specification not stated	3427	Category	Pass Spec
Rhode Island	Filter	Actions	Specification not stated	3427	Category	Pass Spec
South Carolina	Filter	Actions	Specification not stated	3427	Category	Pass Spec
South Dakota	Filter	Actions	Specification not stated	3427	Category	Pass Spec
Tennessee	Filter	Actions	Specification not stated	3427	Category	Pass Spec
Texas	Filter	Actions	Specification not stated	3427	Category	Pass Spec
Utah	Filter	Actions	Specification not stated	3427	Category	Pass Spec
Vermont	Filter	Actions	Specification not stated	3427	Category	Pass Spec
Virginia	Filter	Actions	Specification not stated	3427	Category	Pass Spec
Washington	Filter	Actions	Specification not stated	3427	Category	Pass Spec
West Virginia	Filter	Actions	Specification not stated	3427	Category	Pass Spec
Wisconsin	Filter	Actions	Specification not stated	3427	Category	Pass Spec
Wyoming	Filter	Actions	Specification not stated	3427	Category	Pass Spec

FIG. 2

Compare Performance Specifications
Enter Target Specifications
Step 1: Select paint type
☒ Standard
Step 2: Select paint specifications
Category	☒ Standard: Identity
Specification	☒ Compositional: Binary Chemistry
Category	☒ Requirements: Binary Chemistry
Category	☒ Under Chemistry: Acrylic
Data Type	☒ Category
Category	☒ Target Value
Add specification
View Result
☐ Pass Spec ☐ Fail
State	☒ FASTRAK 3427
☒ Under Chemistry: Generic
☐ pass (excluding not specified)
Federal	☒ specification not stated
Alaska	☒ specification not stated
Alabam	☒ specification not stated
Arkansas	☒ specification not stated
Arizona	☒ specification not stated

FIG. 3

Compare Performance Specifications ⑦
Enter Target Specifications Step 1: Select paint type Standard Step 2: Select paint specifications Category Compositions requirements Specification Glass head type Data Type Category Target Value? ASHTO M277 Add specification Selected Targets Paint Type: Standard <table border="1"> <thead> <tr> <th>Requirement</th> <th>Specification</th> <th>Data Type</th> <th>Target Value</th> </tr> </thead> <tbody> <tr> <td>X</td> <td>Binder identity</td> <td>Category</td> <td>Yes</td> </tr> <tr> <td>X</td> <td>Compositional requirements</td> <td>Category</td> <td>Yes</td> </tr> <tr> <td>X</td> <td>Application</td> <td>Category</td> <td>ASHTO M277</td> </tr> <tr> <td>X</td> <td>Glass head type</td> <td>Category</td> <td>M277</td> </tr> </tbody> </table> View Result <table border="1"> <thead> <tr> <th>State</th> <th>◆ FASTRACK 3427</th> <th>◆ Binder chemistry</th> <th>◆ Glass head type</th> <th>◆ # of pass (excluding not specified)</th> </tr> </thead> <tbody> <tr> <td>Federal</td> <td>specification not stated</td> <td>Yes</td> <td>specification not stated</td> <td>1</td> </tr> <tr> <td>Alaska</td> <td>specification not stated</td> <td>Yes</td> <td>ASHTO M277</td> <td>2</td> </tr> <tr> <td>Alabama</td> <td>specification not stated</td> <td>specification not stated</td> <td>specification not stated</td> <td>0</td> </tr> <tr> <td>Arkansas</td> <td>Yes</td> <td>ASHTO M277</td> <td>Type 1</td> <td>2</td> </tr> <tr> <td>Arizona</td> <td>specification not stated</td> <td>specification not stated</td> <td>ASHTO M277 Type 1</td> <td>0</td> </tr> </tbody> </table>						Requirement	Specification	Data Type	Target Value	X	Binder identity	Category	Yes	X	Compositional requirements	Category	Yes	X	Application	Category	ASHTO M277	X	Glass head type	Category	M277	State	◆ FASTRACK 3427	◆ Binder chemistry	◆ Glass head type	◆ # of pass (excluding not specified)	Federal	specification not stated	Yes	specification not stated	1	Alaska	specification not stated	Yes	ASHTO M277	2	Alabama	specification not stated	specification not stated	specification not stated	0	Arkansas	Yes	ASHTO M277	Type 1	2	Arizona	specification not stated	specification not stated	ASHTO M277 Type 1	0
Requirement	Specification	Data Type	Target Value
X	Binder identity	Category	Yes
X	Compositional requirements	Category	Yes
X	Application	Category	ASHTO M277
X	Glass head type	Category	M277
State	◆ FASTRACK 3427	◆ Binder chemistry	◆ Glass head type	◆ # of pass (excluding not specified)
Federal	specification not stated	Yes	specification not stated	1
Alaska	specification not stated	Yes	ASHTO M277	2
Alabama	specification not stated	specification not stated	specification not stated	0
Arkansas	Yes	ASHTO M277	Type 1	2
Arizona	specification not stated	specification not stated	ASHTO M277 Type 1	0
= Pass Spec ☐ 0 ☒ 1 ☐ 2 □ Pass □ Fail

FIG. 4

Compare Performance Specifications ⑦
Enter Target Specifications Step 1: Select paint type Standard Step 2: Select paint specifications Category Performance requirements Specification No pick-up time (minutes) Data Type Numeric Target Value? 10 Add specification
View Result Selected Targets Paint Type: Standard Requirement Specification Data Type Target Value
<table border="1" style="width: 100%; border-collapse: collapse;"> <thead> <tr> <th style="width: 10%;">Category</th> <th style="width: 10%;">Requirement</th> <th style="width: 10%;">Specification</th> <th style="width: 10%;">Data Type</th> <th style="width: 10%;">Target Value</th> </tr> </thead> <tbody> <tr> <td>Standard</td> <td>× Binder identity</td> <td>PAINTACK 3427</td> <td>Category</td> <td>Yes</td> </tr> <tr> <td>Standard</td> <td>× Compositional Requirements</td> <td>Binder chemistry: acrylic</td> <td>Category</td> <td>Yes</td> </tr> <tr> <td>Standard</td> <td>× Application Requirements</td> <td>Glass bead type</td> <td>Category</td> <td>AASHTO M247</td> </tr> <tr> <td>Standard</td> <td>× Performance Requirements</td> <td>No-pick-up time (minutes)</td> <td>Numeric</td> <td>10</td> </tr> </tbody> </table>						Category	Requirement	Specification	Data Type	Target Value	Standard	× Binder identity	PAINTACK 3427	Category	Yes	Standard	× Compositional Requirements	Binder chemistry: acrylic	Category	Yes	Standard	× Application Requirements	Glass bead type	Category	AASHTO M247	Standard	× Performance Requirements	No-pick-up time (minutes)	Numeric	10
Category	Requirement	Specification	Data Type	Target Value
Standard	× Binder identity	PAINTACK 3427	Category	Yes
Standard	× Compositional Requirements	Binder chemistry: acrylic	Category	Yes
Standard	× Application Requirements	Glass bead type	Category	AASHTO M247
Standard	× Performance Requirements	No-pick-up time (minutes)	Numeric	10
Filter data... General Alaska Arkansas Arizona No pick-up time (minutes) max Specification not stated AASHTO M247 Specification not stated AASHTO M247 Type 1
Pass Spec Fail Pass Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
0 1 2 3 Pass Spec Fail
<div style="border:

FIG. 5

Compare Performance Specifications
Enter Target Specifications
Step 1: Select paint type
☒ Standard
Step 2: Select paint specifications
Category	Selected Targets
Specifications	Paint Type: Standard
Category	Requirement
Specifications	Specification
Category	Data Type
Specifications	Target Value
Category	Requirement
Specifications	Specification
Category	Data Type
Specifications	Target Value
Category	Requirement
Specifications	Specification
Category	Data Type
Specifications	Target Value
Add specification
View Result
= Pass Spec
Fail
☐ Pass
☐ Fail
◆ # of pass (excluding not specified)
<table border="1"> <thead> <tr> <th>◆ State</th> <th>◆ Binder chemistry</th> <th>◆ Glass bead type</th> <th>◆ No pick-up time (minutes) max</th> <th>◆ Viscosity, cP</th> </tr> </thead> <tbody> <tr> <td>◆ Federal</td> <td>◆ Binder chemistry</td> <td>◆ Glass bead type</td> <td>◆ No pick-up time (minutes) max</td> <td>◆ Viscosity, cP</td> </tr> <tr> <td>Alaska</td> <td>specification not stated</td> <td>Yes</td> <td>specification not stated</td> <td>10</td> </tr> <tr> <td>Alabama</td> <td>specification not stated</td> <td>Yes</td> <td>specification not stated</td> <td>10</td> </tr> <tr> <td>Arizona</td> <td>specification not stated</td> <td>Yes</td> <td>specification not stated</td> <td>10</td> </tr> <tr> <td>Arkansas</td> <td>specification not stated</td> <td>Yes</td> <td>specification not stated</td> <td>10</td> </tr> <tr> <td>Arizona</td> <td>specification not stated</td> <td>Yes</td> <td>specification not stated</td> <td>10</td> </tr> </tbody> </table>		◆ State	◆ Binder chemistry	◆ Glass bead type	◆ No pick-up time (minutes) max	◆ Viscosity, cP	◆ Federal	◆ Binder chemistry	◆ Glass bead type	◆ No pick-up time (minutes) max	◆ Viscosity, cP	Alaska	specification not stated	Yes	specification not stated	10	Alabama	specification not stated	Yes	specification not stated	10	Arizona	specification not stated	Yes	specification not stated	10	Arkansas	specification not stated	Yes	specification not stated	10	Arizona	specification not stated	Yes	specification not stated	10
◆ State	◆ Binder chemistry	◆ Glass bead type	◆ No pick-up time (minutes) max	◆ Viscosity, cP
◆ Federal	◆ Binder chemistry	◆ Glass bead type	◆ No pick-up time (minutes) max	◆ Viscosity, cP
Alaska	specification not stated	Yes	specification not stated	10
Alabama	specification not stated	Yes	specification not stated	10
Arizona	specification not stated	Yes	specification not stated	10
Arkansas	specification not stated	Yes	specification not stated	10
Arizona	specification not stated	Yes	specification not stated	10

FIG. 6

FIG. 7